UNITED STATES PATENT OFFICE

HORACE M. BRIDGEWATER, OF STRATFORD, CONNECTICUT, ASSIGNOR TO THE ARTISTIC BRONZE COMPANY, OF BRIDGEPORT, CONNECTICUT, A CORPORATION OF CONNECTICUT

DESIGN FOR A COMBINATION BOTTLE OPENER AND DISPENSING APPARATUS

Application filed May 14, 1932. Serial No. 43,805. Term of patent 3½ years.

To all whom it may concern:

Be it known that I, HORACE M. BRIDGEWATER, a citizen of the United States, residing at Stratford, county of Fairfield, State of Connecticut, have invented a new, original, and ornamental Design for a Combination Bottle Opener and Dispensing Apparatus, of which the following is a specification, reference being had to the accompanying drawing, forming part thereof.

Fig. 1 is a front elevational view of a combination bottle opener and dispensing apparatus showing my new design; and

Fig. 2 is a side elevational view of the same.
I claim:

The ornamental design for a combination bottle opener and dispensing apparatus, substantially as shown.

HORACE M. BRIDGEWATER.
